UNITED STATES PATENT OFFICE

151,001

DESIGN FOR A LAUNDRY MACHINE

Frederick W. Perl, Mansfield, Ohio, assignor to
Westinghouse Electric Corporation, a corpora-
tion of Pennsylvania

Application December 18, 1947, Serial No. 143,213

Term of patent 14 years

(Cl. D49—1)

To all whom it may concern:

Be it known that I, Frederick W. Perl, a citizen of the United States, residing at Mansfield, in the county of Richland and State of Ohio, have invented a new, original, and ornamental Design for a Laundry Machine, of which the following is a specification, reference being had to the accompanying drawing, forming a part thereof.

Figure 1 is a perspective view of a laundry machine, embodying my new design; and

Figure 2 is a section taken along the line II—II of Figure 1 to illustrate the contour of a portion of the front outer surface of the laundry machine.

The opposite end of the laundry machine not in view is similar in appearance to the end shown.

I claim:

The ornamental design for a laundry machine, substantially as shown and described.

FREDERICK W. PERL.
